[57] CLAIM

The ornamental design for a shell for enlarged cab pickup truck, as shown and described.

DESCRIPTION

FIG. 1 is a right side perspective view of a shell for enlarged cab pickup truck, showing my new design;

FIG. 2 is a reduced left side elevational view thereof, it being understood that the right side is a mirror image thereof;

FIG. 3 is a reduced left side perspective view thereof;

FIG. 4 is a left side view of a second embodiment of a shell for enlarged cab pickup truck, showing my new design, the only difference being the omission of the window, it being understood that the right side is a mirror image thereof;

FIG. 5 is a left side perspective view of the shell of FIG. 4, it being understood that the opposite side is a mirror image thereof;

FIG. 6 is a rear view of the shell of FIG. 1 and FIG. 4; and,

FIG. 7 is reduced top plan view of the shell of FIG. 1. The front and bottom of the shell are plain and unornamented.

The broken line showing of environment is for illustrative purposes only and forms no part of the claimed design.
